UNITED STATES PATENT OFFICE.

MARIUS P. HOY, OF ROSEDALE, WASHINGTON, ASSIGNOR OF ONE-HALF TO
CHAUNCEY S. UPRIGHT, OF TACOMA, WASHINGTON.

ANCHOR MECHANISM FOR BOATS.

SPECIFICATION forming part of Letters Patent No. 663,174, dated December 4, 1900.

Original application filed June 9, 1899, Serial No. 719,995. Divided and this application filed June 9, 1900. Serial No. 19,773.
(No model.)

To all whom it may concern:

Be it known that I, MARIUS P. HOY, a citizen of the United States, residing at Rosedale, in the county of Pierce and State of Washington, have invented certain new and useful Improvements in Anchor Mechanism for Boats; and I do hereby declare the following to be a full, clear, and exact description of the invention, such as will enable others skilled 10 in the art to which it appertains to make and use the same.

My invention relates to improvements in anchor mechanism for boats, and particularly for life-boats.

15 It consists of certain novel constructions, combinations, and arrangements of parts, as will be hereinafter fully described and claimed.

In the accompanying drawings, Figure 1 20 represents a side elevation of a life-boat, a portion of the same being broken away and shown in section to reveal the manner of mounting the anchor mechanism. Fig. 2 represents a vertical transverse section through 25 the boat on a line with the anchor-tube.

My improved anchor mechanism may be applied to boats of various kinds; but, as illustrated in the drawings, it is preferably adapted for use in connection with life-boats constructed in accordance with an application 30 filed on the 9th day of June, 1899, Serial No. 719,995, and is a division of said application.

In attaching an anchor to a boat I find it preferable to so locate the same that the pull 35 of the anchor-chain will not be directly upon the bow of the boat, so as to tend to draw the same beneath the water or waves thereof. I therefore, as shown in Fig. 1 of the drawings, pass a vertically - arranged tube, as at 1, 40 through the boat 2, the said tube being open at its lower end and extending to a point near the top of the boat. Near the upper end of the tube an enlargement is formed, as 3, adapted to receive a pulley or sprocket-wheel 4, 45 over which the chain 5 of the anchor is adapted to pass. The chain extends from the pulley downwardly through the tube 1 and thence along a groove 6, formed in the under edge of the keel 7 of the boat. The groove 6 extends to the prow of the boat, and the anchor-

chain, when the anchor is not in use, lies in the said groove, while the anchor 8, attached to the end thereof, is preferably hung upon a hook, as 9, secured to the bow of the boat. The anchor and chain may be of any desired 55 construction and are made of a size to correspond with the size of the boat upon which they are used. The inner end of the chain extends into the exterior of the boat and may be located in a box or casing, as at 10, formed in 60 the interior of the boat. When it is desired to use the anchor for holding the boat at any given point, the anchor is released from the hook 9 and permitted to drop into the water. The chain is then allowed to pay out from 65 the inside of the boat until the anchor obtains a suitable hold upon the bottom of the water upon which the boat is floating. By this arrangement it will be seen that the pull upon the anchor-chain is so arranged that it has 70 not sufficient leverage upon the bow of the boat to depress the same in the water or cause waves to break over the prow. When it is desired to raise the anchor, the chain is pulled in over the pulley 4 to a suitable extent until 75 the anchor approaches the boat, and then by passing a suitable grapple beneath the bottom of the boat the chain or anchor may be grasped and hauled to the upper side of the boat and hung upon the hook 9. The chain 80 may then be made sufficiently taut to lie snugly in the groove 6.

It will be apparent that this mechanism may be applied to boats of various constructions without departing from the spirit of the invention, the essential features being the use 85 of a tube arranged about midway between the prow and the center of the boat and means for carrying the chain and supporting the anchor.

90 The parts of my invention are exceedingly simple and yet are very effective for accomplishing the purposes desired.

Having thus described my invention, what I claim as new, and desire to secure by Letters 95 Patent, is—

1. An anchor mechanism for boats, comprising an anchor, a chain carrying the same, an inclosing tube arranged in the boat for receiving the anchor-chain and extending up- 100

wardly through the boat, the said tube being open at the bottom to the water, a pulley housing at the top of the tube, a pulley located in said housing, the said housing having an opening through which the chain may pass into the boat so that the anchor may be hoisted or lowered from the inside of the boat, substantially as described.

2 An anchor mechanism for boats, comprising an anchor, a chain carrying the same, a vertical tube arranged in the hull or body of the boat, open to the water at its lower end and extending a suitable distance above the water interiorly of the boat, a sprocket 15 wheel or pulley arranged at the upper end of the tube for movably supporting the chain, and a hook upon the prow of the boat, for supporting the anchor when not in use, the said chain being adapted, when the anchor is 20 secured to the hook, to lie in a groove formed in the keel of the boat, substantially as described.

3. An anchor mechanism for boats, comprising a chain carrying an anchor, a tube mounted in the boat and extending through the keel thereof, the said keel being also provided with a chain-receiving groove which extends forward to the prow of the boat, the said tube being arranged at a point about midway between the bow and center of the 25 boat, a pulley mounted in the upper end of the tube over which the chain may be pulled for raising or lowering the anchor, a box or casing in the boat for receiving the loose end of the chain, and a hook upon the prow of the 30 boat for receiving the anchor when not in use, substantially as described.

In testimony whereof I hereunto affix my signature in presence of two witnesses.

MARIUS P. HOY.
